UNITED STATES PATENT OFFICE.

RODNEY N. MCCLURE, OF INGLEWOOD, CALIFORNIA.

DRAPERY ROD SUPPORT.

Application filed June 8, 1927. Serial No. 197,313.

This invention relates to a curtain fixture and particularly pertains to a bracket for supporting curtain rods.

An object of the invention is to provide a curtain rod support which is especially applicable for use on hinged windows and to provide a means whereby a hinge of a window may be utilized as a means of holding the curtain rod support so as to obviate fastening the support directly to the window casing.

Another object is to provide a curtain rod supporting bracket which is adaptable to the carrying of either one or a plurality of curtain rods whereby a variety of draping effects may be readily produced such as by a main curtain alone or with either side drapes, or valances, or both, and whereby separate and independent rods may be provided on a single bracket for main curtains, side drapes, valances and other hangings.

Another object is to provide a curtain rod supporting bracket of simple construction and economical manufacture, and which may be easily and quickly applied.

With the foregoing objects in view together with such other objects and advantages as may subsequently appear, my invention resides in the parts and in the combination, construction and arrangement of parts hereinafter described and claimed and illustrated by way of example in the accompanying drawing, in which:

Fig. 1 is a plan view illustrating the application of the invention to a window having a pair of hinged sashes;

Fig. 2 is a view in front elevation of the structure shown in Fig. 1;

Fig. 3 is a perspective view of a main rod supporting bracket illustrating the manner of supporting same on a hinge;

Fig. 4 is a perspective view of a supplemental rod supporting bracket adapted to be employed in conjunction with the main bracket;

Fig. 5 is a perspective view illustrating the manner of assembling the main and supplemental brackets;

Fig. 6 is a perspective view of the supplemental bracket showing it as adapted to support a pair of rods;

Fig. 7 is a view of the supplemental bracket showing it as adapted to support a pair of rods;

Fig. 8 is a perspective view showing a modification of the invention in which the

main bracket is adapted to be mounted directly on a window sash or casing.

Referring to the drawings more specifically A indicates generally a main rod supporting bracket and B designates a supplemental rod supporting bracket. The bracket A as shown in Fig. 3 embodies a stem portion 10 which is adapted to be inserted in a hinge C in substitution of the hinge pintle; 60 the stem 10 being fitted with an adjustable collar 11 adapted to seat on the upper edge of the hinge to afford a support for the bracket. A set screw 12 is provided on the collar to hold the latter against movement 65 on the stem. The upper portion of the stem is bent inwardly as indicated at 13 and is then bent horizontally as indicated at 14 to provide a portion which is adapted to extend parallel with a window casing as shown in 70 Fig. 1; there being an outwardly extending portion 15 leading from the portion 14 which terminates in an eye 16 with which a curtain rod 17 may be hingedly connected. The supplemental bracket B embodies a 75 body portion 18, the lower end of which is formed with a hook 19 and a notch 20. The supplemental bracket is designed to be connected to the main bracket by setting the notch 20 over the horizontal extension 15 80 with the hook portion 19 projecting beneath the portion 14 as shown in Fig. 5. The body portion 18 extends upwardly and outwardly at an inclination so that the weight of the outer end portion of the supplemental bracket and a load imposed thereon will tend 85 to maintain the hooked end thereof in engagement with the main bracket. The outer end of the supplemental bracket is formed with a forwardly projecting flange 21 of 90 suitable construction adapted to form a support for a curtain rod 22 which may be affixed thereto in any desired manner. When 95 it is desired to support a plurality of rods on the supplemental bracket the latter may 100 be formed with a plurality of the rod engaging flanges 21 as indicated at *a* and *b* in Fig. 6 and at *c*, *d* and *e* in Fig. 7.

In Figures 1 and 2 the invention is illustrated as applied to a hinged window having 105 double sash in which instances the main brackets A are attached to the hinges C and the curtain rods 17 hinged to the eyes 16 at the upper outer ends of the main brackets are telescoped with rod sections 23 the outer ends of which are carried on brackets 24 affixed to the window sash; and the curtain

rods 22 carried by the supplemental brackets are connected together by a telescoping rod section 25. It will be noted that by this arrangement the rods carried by the supplemental brackets will extend on a plane above and extending outwardly beyond the front face of the rods 17 and 23 and beyond the hinged ends of the rods 17 which provides a desirable arrangement for valances and side drapes. Where it is desired to increase the number of rods above the main supporting rods a supplemental bracket such as shown in Figs. 6 and 7 may be employed.

In some instances, it may be desirable to 15 mount the main brackets directly on a sash or window casing in which event it may be formed as shown in Fig. 8 that is with a downwardly projecting portion 26 in lieu of the stem 10 which may be secured in place 20 by screws or similar fastenings.

I claim:

1. A drapery rod support for swinging windows comprising a main bracket including a stem adapted to substitute for a hinge pintle and formed with an angular upper end portion, including a horizontal member and an outwardly extending member adapted to carry a rod on its outer end and a supplemental bracket formed 30 with a notch on its lower edge intermediate its end adapted to seat astride the outwardly extending portion of the main bracket, and formed with a hook engageable with the lower side of the horizontally extending member of the main bracket, and having a rod engaging flange on its outer end spaced upwardly and outwardly from the end portion of the main bracket whereby the weight of the outer end portion of said 40 supplemental bracket will maintain the latter in seated position on the main bracket.

2. A drapery rod support for swinging windows comprising a main bracket including a stem adapted to substitute for a hinge pintle and formed with an angular upper end portion, including a horizontal member and an outwardly extending member adapted to carry a rod on its outer end and a supplemental bracket formed with a notch 50 on its lower edge intermediate its end adapted to seat astride the outwardly extending portion of the main bracket and formed with a hook engageable with the lower side of the horizontally extending member of the main bracket, and having a rod engaging flange on its outer end spaced upwardly and outwardly from the end portion of the main bracket whereby the weight of the outer end portion of said supplemental bracket will maintain the latter in seated position on the main bracket, and means for adjustably supporting said main bracket on a hinge.

3. A drapery rod support for swinging windows comprising a stem adapted to

serve as a pintle for a hinge, a collar on said stem arranged to seat on a hinge engaged by the stem, and a substantially U-shaped member formed on the upper end of said stem extending horizontally, adapted 70 to be hingedly connected at its outer end with a curtain rod.

4. In a device of the character described, a bracket embodying a stem portion which is adapted to be inserted in a hinge as a 75 substitution for its pintle, means on said stem to seat on the upper edge of the hinge to support said bracket, said stem having an inwardly bent portion above the hinge to bring the top portion of the bracket close 80 to the wall, said inwardly bent portion being then continued in a horizontal direction substantially parallel to the wall and terminating in a portion which projects outwardly from the wall, said terminal portion 85 being adapted to support one end of a curtain rod; and a supplemental bracket having at its inner end a hook adapted to underlie one of the horizontal portions of said stem and between its ends a portion adapted 90 to seat upon another horizontal portion of said stem, and an outer end adapted to support an object, the weight of which will maintain said supplemental bracket in the operative position.

5. A curtain rod support for double swinging windows comprising a bracket mounted on the sash of each window on the side opposite the hinge, a second set of brackets each provided with a stem adapted 100 to substitute for a hinge pintle of each window, extensible curtain rods adapted to swing with the windows hingedly connected at one end to each of said second brackets and supported at the opposite ends by said 105 first mentioned brackets, a second stationary curtain rod, adapted to span both windows, and means for mounting said second rod upon said second set of brackets.

6. A curtain rod support for double swinging windows comprising a bracket mounted on the sash of each window on the side opposite the hinge, a second set of brackets each provided with a stem adapted to substitute for a hinge pintle of 110 each window, and having a hinge point extended beyond the hinging line of the window, a pair of extensible curtain rods adapted to swing with the windows and hinged at one end to said hinge point and 115 supported at the opposite ends by said first mentioned brackets, a second stationary curtain rod adapted to span both windows spaced upwardly and outwardly from said first mentioned rods, and means for mounting 120 said second rod upon said second set of brackets.

In testimony whereof, I have affixed my signature.

RODNEY N. McCLURE.
